Specification for Design.

Patented Feb. 10, 1914.

Application filed March 19, 1913. Serial No. 755,550. Term of patent 14 years.

To all whom it may concern:

Be it known that I, GEORGE P. ALTENBERG, a citizen of the United States, residing at Cincinnati, in the county of Hamilton and State of Ohio, have invented a new, original, and ornamental Design for a Holder for Carafes, of which the following is a specification, reference being had to the accompanying drawing, forming part thereof.

My new, original and ornamental design for a holder for carafes is shown in the accompanying drawing, in which:

Figure 1 is a perspective view of the holder. Fig. 2 is a side elevation of the same; and, Fig. 3 is an end elevation of the same.

I claim:

The ornamental design for a holder for carafes, as shown.

GEORGE P. ALTENBERG.
